UNITED STATES PATENT OFFICE

ALVAH M. GRIFFIN, OF LOS ANGELES, CALIFORNIA, ASSIGNOR, BY MESNE ASSIGNMENTS, TO CHICAGO BRIDGE & IRON COMPANY, OF CHICAGO, ILLINOIS, A CORPORATION OF ILLINOIS

SEAL FOR FLOATING DECKS

Application filed February 23, 1927, Serial No. 170,169. Renewed May 29, 1929.

This invention relates to a seal for a floating deck such, for example, as is employed in oil storage tanks.

An object of the present invention is to provide a seal for a floating deck incorporating means for rendering the seal gas-tight.

Another object of the present invention is to provide a seal of fireproof construction.

Another object of the present invention is to provide a seal of exceptional efficiency and simplicity of construction and operation.

Various further objects and advantages of the invention will be apparent from a description of a preferred example of a seal for a floating deck embodying the present invention. For this purpose, reference is made to the accompanying drawing in which the seal is illustrated.

In the drawing:

20 Figure 1 is an elevation partially in vertical section of a fragment of a floating deck and tank disclosing the new seal construction in extended position.

25 Figure 2 is a similar view with the seal in the normal position.

Figure 3 is a similar view with the seal in compressed position.

Figure 4 is a development of the seal.

30 Figure 5 is a section through the seal, and,

Figure 6 is a section through the curtain disclosing the details of the joints in the curtain.

Referring to the drawing, 2 indicates the side wall of the tank employed, for example, in holding oil and 3 indicates a fragment of a floating deck mounted within the tank 2, said floating deck having a bottom wall 4 and a circumferential wall 5. The floating deck

35 may be of the open or dish-pan construction or may have a top wall 6 defining an enclosed air chamber 7, and the tank may be formed in one or a plurality of sections with one or a plurality of enclosed air chambers. At the

40 top of the circumferential wall of the floating deck, there is bolted by bolts 8 sections of angle irons 9 to which are attached hinges 10.

Said hinges support outer sealing plates 11 which extend downwardly into the liquid, supporting the tank 3, being curved inwardly at their lower ends as indicated at 12. The

outer sealing plates 12 each have one side offset as indicated at 13 in Figure 5, and adjacent sealing plates overlap in the offsets so that all of the sealing plates 11 have their outer walls substantially flush. 53

The bolts 8 also engage and support the upper end of a curtain 14 which extends continuously around the floating deck, the ends of the curtains being joined together by wire staples 15 or other suitable means. Said curtain extends downwardly behind the sealing plates 11 substantially to the lower end of the sealing plates 11. The curtain is formed of a gas-tight material, such as an asbestos roofing or paper. 60 65

The curtain 14 is held pressed against the inner surface of the sealing plates 11 by loader plates 16, one of which engages each of the sealing plates 11, said loader plates being hinged to the side wall 5 of the floating deck 70 as indicated at 17. The loader plates extend downwardly to the curved portion of the sealing plates 11 and hence are curved rearwardly and serve to support the outer end of conical coil springs 18, the other end of which are attached to the side walls 5 of the floating deck 3, as indicated at 19. 75

The herein described seal is rendered gas-tight due to the pressing of the curtain 14 against the sealing plates by the loader plates 80 and springs 15 and 18, thereby positively cutting off all passage of gas around the edge of the floating deck 3. In this manner, all of the gas from below the deck is prevented from escaping and accumulating on the top of the 85 deck and any danger of fire thus entirely avoided.

While the device herein described is well adapted to carry out the objects of the present invention, it is understood that various 90 modifications and changes may be made without departing from the principles of the invention and the invention includes all such modifications, changes, and substitution of equivalents as come within the scope of the 95 following appended claims.

It is to be noted that the curtain 14 is continuous and serves as a sealing liner for the plates 11. By means of this construction considerable gas pressure can be held. In 100

cases of excess pressure, the curtain 14 is pressed outwardly against the plates 11 and supported by the latter, thus preventing the curtain from tearing or ripping, or having its 5 lower edge pulled out of the liquid. There is thus provided a gas-tight curtain that is also capable of withstanding or holding considerable pressure.

I claim:

- 10 1. In a sealing construction for volatile liquid, the combination of a tank for the liquid, a floating deck supported on the liquid in the tank, a plurality of plates hinged to the deck, means for yieldingly pressing the 15 plates against the wall of the tank, and a continuous flexible gas-tight curtain sealing the space between the deck and the plates, said curtain having its inner edge adjacent the deck and its outer edge adjacent the plates, 20 and its intermediate portion of such formation as to be movable under gas pressure into position as a sealing liner for the plates.
2. Apparatus as claimed in claim 1 in which the curtain has its outer edge disposed below the level of the liquid.
- 25 3. Apparatus as claimed in claim 1 in which the plates are overlapping.
4. Apparatus as claimed in claim 1 in which the curtain has its outer edge disposed 30 below the level of the liquid and in which the plates are overlapping.
5. Apparatus as claimed in claim 1 in which the curtain has its outer edge adjacent the plates substantially at their point of contact 35 with the wall of the tank.
6. Apparatus as claimed in claim 1 in which the outer edge of the curtain is disposed below the level of the liquid and is adjacent the plates substantially at their point 40 of contact with the wall of the tank.

Signed at Los Angeles, California, this 9th day of February 1927.

ALVAH M. GRIFFIN.
